TELEVISION APPARATUS

Volney D. Hurd, Dover, Mass.

Application October 21, 1936, Serial No. 106,767

4 Claims. (Cl. 178—6)

The present invention relates to the art of television and in particular to a method and system of scanning that has for its purpose the production of improved television pictures and more efficient and cheaper scanning means than at presently used.

The art of picture transmission has been the object of development work for a great many years. The methods initially employed are chiefly of a mechanical nature and more recently these methods have been generally disregarded as the use of vacuum tube control means has become publicized.

The general television systems may be separated into two classes, the so-called mechanical method of scanning and the scanning with the use of a cathode beam commonly embodied in the cathode ray tube. The mechanical scanning system is somewhat misnamed since it employs electrical means. The chief distinctions however between the two systems is that in the mechanical scanning method, a scanning disc is employed by which a light beam is made to travel a certain definite course. In the system employing the cathode ray tube, the cathode beam corresponds to the light beam and this is made to scan the object whose image is to be transmitted by electrical control of the course of the beam.

The present invention relates in fact to both methods of scanning and may be applied equally to each method to produce the improved results. The invention similarly applies to the system used at the reproducing end as may well be expected since the reproducing end must always be related in synchronism of movement with the movement of the beam at the transmitting end.

The invention also applies with particular merit to a mechanical scanning system not only on account of the simple mechanism which may be incorporated in the mechanical means to produce the desired result, but also because it allows the mechanical system to overcome certain objectionable features which have previously been present in systems of this nature.

With all the development in the art of television which has taken place since its inception, the art itself has up to the present time been retarded in its full commercial development for a number of reasons. The cost of the apparatus is still too expensive to allow widespread sale. In addition to this the radio channels over which the signals must be transmitted are limited and the apparatus itself is still too imperfect to produce results that can readily be enjoyed. The limitation of the channel over

which the transmission must be made is caused not only because of the lack of the so called broad band of frequencies available, but also because television to be transmitted perfectly must be given a very broad channel frequency in order to provide proper definition of the pictures to be transmitted, that is to say, the picture frequency is directly related to the necessary band frequency width and with a high enough picture frequency and line frequency to provide a proper picture definition, the channel band frequency must be beyond the limits that ordinarily are possible to assign.

The present invention is particularly adaptable to overcome these difficulties and to provide a clear definition of the picture with a lower line frequency or with the same line frequency at present available. The present invention is chiefly concerned with overcoming these particular difficulties and amongst other things provides in its selection of frames a composite picture which multiplies the clearness of the definition of the picture itself. This will be more readily understood from the description given in the specification below. The present invention also provides these results in a simple mechanism and further furnishes a simple scanning means which in its various features produces a more perfect picture than has been possible before.

The present type of invention also contemplates using a particular type of screen and may also employ particular scanning means as described below.

In addition to the above, where a mechanical means is employed, as for instance a drum or disc, or even with pure electrical methods, the scanning spot may be narrower in the direction that it moves and wider in the direction normal to it. Using this type of beam or opening, clear definition of the picture will be obtained in a direction normal to the scanning because of the overlapping effect as will be noted below, and in addition to this, clear definition will be obtained in the direction of the motion of the beam because of the narrowness of the spot which may be employed.

The invention will be further described in connection with the drawings, in which:

Figure 1 illustrates more or less diagrammatically the scanning system preferably employed.

Figure 2 shows the application of such a system in combination with a feature of criss-cross scanning.

Figure 3 shows a further modification of the system as set forth in Figure 2.

Figure 4 shows a detail of an element indicated in Figure 3.

5 Figure 5 shows a further modification of the system indicated in Figure 2.

Figure 6 shows a fragmentary view of the details of the screen.

10 Figure 7 shows a cross sectional view of the element shown in Figure 6.

Figure 8 shows a still further modification of a selective line scanning drum, and

15 Figure 9 shows an auxiliary view taken on a section 9-9 of Figure 2.

15 In the arrangement shown in Figure 1, the system may be considered as the receiving end in which the light tube 1 responds to the current impulses transmitted by the wires 2-2 to produce a light image of an intensity corresponding 20 to that at the same instant at the transmitting end. The light may be transmitted through a concentrated lens 3 and passed through the slots 4, 4, 4, etc., in the disc 5 and reflected from the mirror 6 to the screen 7. The spot image in the 25 screen may be rectangular with the narrow dimensions in the direction that the spot is moved. In the arrangement shown in Figure 1, the disc 5 is the scanning disc and is driven by means of the shaft 8 through the motor 9 which is run in synchronism with the transmitter system. Carried to the shaft of the motor 9 at the opposite end is a gear 10 which operates a second gear 11 in a reduction system which in turn drives the mechanism which will be described presently.

35 The mirror 6 is pivoted in supporting bearings 12 and 13 so that it is free to be moved slightly about a vertical angle. Carried by the mirror frame is the arm 14 which is tensioned to the cabinet 15 by means of the spring 16. The end 40 of the arm 14 carries a dependent V 17 bearing upon a cam 18 which is mounted on the shaft 19 also carrying the gear 20. The gear 20 meshes with the worm 21 which is slidably mounted upon the shaft 22 by means of the ribbing 23 so that the worm may be placed by 45 moving the handle 24 carrying the support 25 in any position along the shaft. In this way the position of the cam under the dependent V 17 may be adjusted to the desired point and thus 50 the mirror 6 may have its inclination changed to produce the results desired. The shaft 22 is driven through the gears 26 and 27, the gear 27 being mounted on a shaft 28 which is driven by the gear 11 mentioned above.

55 In the operation of the system each hole in the scanning disc 4, 4, causes the beam of light to sweep across the screen, successive holes being so positioned that different lines are scanned with each hole until all of the lines as indicated 60 in the screening 7 may be scanned. This may be accomplished by a single revolution of the screen disc 5, or it may be accomplished in part of a revolution dependent of course upon the arrangement of holes and the speed of scanning.

65 If the scanning drum shown in Figure 8 is used, the scanning of a single frame may be accomplished by, what I call, an X scanning method. In this case the scanning slot 30 furnishes the first line of scanning, 81, the second, 82 the 70 third, 83 the fourth and so on, the position of the scanning slots forming the shape of a letter.

In this method of scanning the whole picture is filled in over its entire surface more or less uniformly, that is to say, the picture does not 75 grow from the top down or from the bottom up,

but the successive lines scanned are so distributed over the whole picture, that the whole picture takes a gradual form. This method has a tendency of eliminating the flicker that is commonly present in other methods of scanning.

5 In order to produce the picture that is transmitted at the sending end, it is of course necessary to repeat the same pattern that the scanning disc at the transmitting end is going through. This may obviously be done by having the motor 9 operate in exact synchronism with the scanning mechanism at the transmitting end and having a disc 5 exactly the same as the transmitting disc at the transmitting end. In addition to this mechanism however in the present system, the transmitting end must have a corresponding mirror system, the inclination of which is governed in accordance with a device like that shown in the present figure.

If the mirror in the present case were omitted, 20 then each line that was scanned at the transmitting end of each line that was produced at the receiving end would correspond and would repeat itself in one scanning cycle. Therefore if a picture were a 60 line picture, the picture 25 would repeat itself in exactly the same position for each 60th line.

The present mechanism produces a different scanning arrangement and has for one of its chief objects the reproduction of the picture to 30 be transmitted by successive different scannings. If the picture is to be scanned with 60 lines for one frame, then the present arrangement scans the next frame, not in the same 60 lines as in the original frame but with 60 lines that are 35 somewhat displaced. The third frame may similarly be slightly displaced from the second frame so that no two successive frames will scan the same lines.

40 In the mechanism therefore in the present application, it will be noted that the cam 18 moves the arm 14 very slightly in a complete revolution which is so adjusted to extend over a considerable number of frames. The line 30 scanned in the mechanism as shown, when repeated on the next 45 scanning will be slightly displaced, since at that time the angle of inclination of the mirror 6 will be such as to throw the line either upwards slightly or downwards as the case may be. The mirror may substantially retain its position over a 50 complete frame and then at the next frame may take up a second position in which the lines 30 and all of the other lines become slightly displaced. This overlapping of the lines of the picture bring out the definition of the elements 55 between the lines and even with a frame of fewer lines provides a more clearly definite picture than where the lines are repeated in exactly the same position. Progression of the inclination of the mirror may be continuous in which case the 60 successive lines in the frame will be varied. The choice of the method to be employed can be wholly accomplished by the proper selection and design of the cam 18. After one cycle of the cam 18 the frames again repeat themselves in the 65 same position, but this interval is large as compared to the interval between successive frames and may even be of another order of magnitude; that is to say, each 10th or 20th frame may repeat itself or if desired of course, the repetition may 70 be cut down so that each 5th frame may repeat itself.

In adjusting the receiving system to correspond to the sending system, the synchronism of the motor 9 is of course established with that of the 75

motor at the transmitting end. If the elements are in exact synchronism the picture will be produced clearly. If however, the mirror 6 has not the proper angle, the picture may be somewhat fuzzy and synchronism of the mirrors can be readily established then by movement of the handle 24 to the right or left as shown in the figure until the proper inclination of the mirror is obtained to sharpen the lines of the picture and the screen. When this occurs the position of the handle is fixed and thereafter complete synchronism will be obtained. It will be observed that the motion of the mirror 6 is extremely slight and at its maximum is not more than the width of a single line. This method of scanning it will be observed is practically equivalent to the production of a picture of lines which is the product of a number of lines in the frame and the number of successive frames until the frame has exactly repeated itself. In this, the applicant has further found that there is no limit to the number of different elements which may be used before a frame is exactly reproduced, the increased improvement however being noticeable with displacements of 5 and 10 frames before reproduction occurs. It is the applicant's estimate that probably the maximum improvement can be obtained with some displacement ranging between 10 and 20 frames.

30 In this method of scanning an ordinary scanning disc is shown. The system may however incorporate a drum in which the light source is obtained in somewhat a different manner. In most so called mechanical methods of scanning there is an inefficient utility of light source, either a whole plate is lighted to obtain a tiny light spot or the scanning is obtained by movement of a lens or mirror from a small lamp source.

40 In the present system the applicant may use a substantially powerful light source which is fixed in such a way that the association of relative positions of the mask and the scanning drum are such as to produce the desired movement of the scanning beam. Instead of using a futile pin-point of light, a spot source 31 giving plenty of intense light is usable. The mask 32 may be positioned in front of the light source and provided with an opening 33 of the desired size. This may be $\frac{1}{8}$ " to $\frac{1}{4}$ " in diameter dependent upon the size 34 of the holes in the drums and the position of the other related parts of the system. As indicated perhaps more clearly in Figure 4, the opening 34 in the drum 35 must be such as to sweep the beam 36 across the mirror 37 and produce a corresponding line across the screen 38. The drum 35 may be rotated in the same manner as the scanning disc 5 of Figure 1 and the varying of the position of the line across the screen 38 may be accomplished by moving the mirror 37 in a manner similar to that of the mirror 6 in Figure 1. The light from the mirror 37 is concentrated by means of a lens 39 which focusses on the screen 38. The type of scanning indicated in Figure 3 is so called spiral scanning since the holes 34, 34, etc. on the disc 35 are arranged in a helical spiral in which each opening in the drum corresponds to one line, that is, scanned across the screen 38. The holes 34, 34 on the scanning drum 35 are preferably spaced apart substantially the width of the holes themselves. It should be noted in this respect that as one hole leaves the field of the light beam, for instance the opening 33 in the mask 32, that the next hole approaches the beam so that in this

way uninterrupted successive scanning of successive lines is obtained.

5 In place of this system, the system shown in the mechanism in Figure 2 may be used. In this, the displacement of the frames may also be accompanied by a criss-cross scanning of the picture. In this figure a scanning disc 40 may be used in which the holes 41 are placed in a spiral arrangement similar to that indicated in Figure 1. There may be as indicated in this figure two sources of light 42 and 45, the source 42 being placed at a point where the holes 41 travel horizontally across it. In front of the disc, there may be positioned a reflecting prism 43, which together with the source and the hole in the disc 15 produces the line 44 as indicated in the figure. The vertical lines are produced by means of the source 45 which is positioned at a place where the holes in the disc pass before the source in a general vertical direction. In front of the disc there 20 is positioned the prism 46 which elements produce the vertical line 47. The displacements of the vertical lines in successive frames in accordance with the device indicated in Figure 1 may be accomplished by control of the prism 46, and 25 similarly the displacement of the horizontal lines may be controlled by movement of the prism 43. The prism 46 is supported for rotary motion by means of the shaft 80 journaled in bearings 81, 81. The displacement of the lines is obtained by 30 means of the mechanism 82 operated by the handle 24 which is the same as that shown in Figure 1. This mechanism is driven by the gear 83 which operates on an extension of the shaft 49 35 and drives the gear 84. The same type of mechanism is used on the prism 43. Preferably, first a vertical frame and then a horizontal frame are scanned, or vice versa, and this may be accomplished as schematically indicated by some switching system associated and synchronized 40 with the control of the scanning disc. In this case the motor 48 driving the scanning disc 40 may also drive on the shaft 49 the gear system 50 and 51 which rotates the shaft 52 carrying the cam 53 controlling the operation of the contacts 54, 55 45 on one side of the cam and 56, 57 on the other side of the cam. As the circuit to one light is closed, so the circuit to the other light is open so that successive first one source is connected and then the other separate circuits may be provided but as indicated in the figure, a single circuit 58 is provided with which the two light sources are in parallel, the switch mechanism being located in each parallel flange. In place of the 90° criss-cross scanning as indicated in Figure 2, a lesser disc may be used as suggested in Figure 5, where the two light sources 59 and 60 are indicated at positions with the axis 61 of the scanning disc 62 at approximately 60°, the screen 63 being scanned in the manner as indicated by the lines thereon. In order to obtain a screening with the best possible visible effect, a screen may be employed as indicated in Figures 6 and 7. In these figures the screen 64 is provided with a great number of convexed or concaved reflecting mirrors 65, the mirrors 65 being preferably smaller than the light source so as to produce reflections in all directions. The screen 64 is preferably of some highly reflective material, such as silver or the like, and the arrangement of a great number of small reflecting mirrors on its surface so reflecting the light falling upon it that the image may be viewed from the side as well as positions directly in front of it. A screen of this type also provides efficient light 75

reflection and makes it possible to see the image even with a comparatively poor light source.

Having now described my invention, I claim:

- 5 1. In a television system, means for scanning comprising a scanning disc having two sources of light, one source of light positioned with relation to the scanning disc for producing one group of parallel lines of scanning, the second source of light being positioned to produce a second group of 10 parallel lines of scanning, each of said groups being positioned relative to the other, and means positioned in front of said scanning disc for controlling the displacement of the scanning from a distance less than the width of the scanning line.
- 15 2. In a television system, means for reconstituting a picture of an object scanned by similar means at the transmitting end, comprising means for producing said picture by successive line developments constituting a frame, means 20 for cyclically varying the position of the lines of the frame by a space less than the width between successive lines and means provided only at the picture producing station for manually ad-

justing the phase of the cycle independent of said picture producing means.

3. In a television system, a picture producing means comprising means for producing a picture by successive line developments comprising the 5 picture frame, means for cyclically advancing the line position in each frame by a comparatively small value and means for advancing or retarding the phase of said cyclic variation to bring the line definition of the picture in clear outline in-¹⁰ dependent of said picture producing means.

4. In a television system, a picture producing means comprising a scanning disc and a light source, means reflecting the beam from the scanning disc to the producing screen, means for producing a displacement of the beam in successive picture frames a small amount in cyclic progression and means manually operative to adjust the phase of the cyclic progression for sharpening the lines of the produced picture independent of ¹⁵ 20 said picture producing means.

VOLNEY D. HURD.
